UNITED STATES PATENT OFFICE.

GEORGE P. BOSWORTH, OF CENTRAL FALLS, RHODE ISLAND, ASSIGNOR TO HEMPHILL COMPANY, OF PAWTUCKET, RHODE ISLAND, A CORPORATION OF MASSACHUSETTS.

STITCH-LENGTH-CONTROLLING MECHANISM FOR KNITTING MACHINES.

Application filed December 20, 1918. Serial No. 267,707.

To all whom it may concern:

Be it known that I, GEORGE P. BOSWORTH, a citizen of the United States, and a resident of Central Falls, in the county of Providence and State of Rhode Island, have invented an Improvement in Stitch-Length-Controlling Mechanism for Knitting Machines, of which the following description, in connection with the accompanying drawings, is a specification, like characters on the drawings representing like parts.

This invention relates to knitting machines and more particularly to means for controlling, changing or varying the effective length of the stitches for any purpose, as, for example, for the purpose of permitting the introduction of a splicing or reinforcing thread or for permitting the effective substitution of a heavier thread, or for shaping the article, which may be a knitted fabric of any type or description. Herein I have disclosed my invention in connection with the knitting of hosiery, but obviously my invention is not limited thereto.

In order that the principle of the invention may readily be understood, I have disclosed a single embodiment thereof in the accompanying drawings, wherein—

Fig. 1 is an end elevation of a knitting machine having my invention applied thereto;

Fig. 2 is a rear elevation of said machine;

Fig. 3 is a plan view of the machine shown in Figs. 1 and 2;

Fig. 4 is a front elevation of the upper part of a knitting machine embodying my invention; and

Figs. 5 and 6 are plan views respectively showing the formation of loops of normal length, and the formation of enlarged loops permitting the introduction of a splicing thread.

It is desirable to change or vary the length of the knitted loops or stitches for various purposes, certain of which I have above referred to. My invention is not limited in its application to any of said purposes or uses, but herein for purposes of illustration I have disclosed my invention as employed primarily to facilitate the introduction of a splicing thread as, for example, a high splicing thread above the heel of a stocking, as well as a reinforcing thread for the toe of the foot.

My invention may be embodied in various

types of knitting machines, whether straight or circular and whether the needles be of a spring beard or latch type. I have herein represented my invention as embodied in a circular knitting machine wherein the 60 needles are of the spring beard type and are carried by a needle cylinder to which movements of rotation and reciprocation are given in the well known manner to effect the formation of hosiery. Obviously the invention may be embodied in the knitting of 65 hand coverings or underwear.

Referring more particularly to the drawings, the frame of the machine is indicated at 1. Therein is mounted the usual drive 70 shaft 2 having fast thereon a pinion 3 meshing with a gear 4 upon the shaft 5 which also has fast thereon a cam plate or disk 6 having elevations 7 and depressions 8 of any suitable number, and herein four of each, 75 because of the timing between the cam plate and the head. The drive shaft 2 is provided with the usual pulleys 9, 10, 11, which may be respectively high speed, low speed and loose.

The knitting machine is provided with the usual needle cylinder 12 wherein are mounted the needles 13 herein represented as spring beard needles. The needles are vertically reciprocated in their grooves by a cam ring 85 13^a carrying cams 13' of any suitable type, as for example, of the general character shown in the patent to Hemphill, No. 933,443. The said cam ring is carried by a cam plate 14 which is supported by upright 80 rods or members 15, one of which is indicated in Fig. 1, and which is operatively associated with the cams upon the cam shaft so that the vertical position of the cam ring may be varied in order to vary the length 85 of the stitches. In the disclosed embodiment of my invention, movements of rotation and reciprocation are imparted to the needle cylinder, but my invention is equally applicable to a construction wherein the 100 needle carrier or cylinder is held stationary and the cam carrier or ring is rotated and reciprocated.

Upwardly extending from the bed 16 of the machine is a fixed post or abutment 17 105 upon the upper end of which is pivoted in any suitable manner a so-called latch ring or guard 18 which herein is represented as partially surrounding the circle of needles. Obviously a complete latch or guard ring of 11

any other suitable character may be employed.

Operatively related to the needle cylinder 12 is a sinker cam ring 19 of suitable character surrounding sinkers 20 of any suitable type and mounted for radial movement in the upper edge of the needle cylinder. These sinkers are adapted to be moved radially by cams of any suitable character, as, for example, by the cams 21, 22, 23, 24, shown in Figs. 5 and 6, for the purpose of engaging the thread between its points of engagement by the needles and thus to cooperate with the needles in the formation of the loops or stitches.

The said sinker cam ring 19 rests loosely upon or about the upper end of the needle cylinder and is held from rotation with the needle cylinder and its needles and sinkers in any suitable manner, as, for example, by means of adjustable screws or stops 25, 26, tapped into ears or lugs 27, 28, carried or formed upon the cam ring. Said ears or lugs 27, 28 are spaced apart somewhat more widely than the width of the post 17 carrying the latch or guard ring 18, thus permitting a certain extent of lost motion between the needle cylinder and the sinker cam ring. This lost motion is preferably provided to permit the proper positioning of the cams of the sinker ring with respect to the cams of the cam ring, that is, with respect to the knitting wave of the knitting needles in a manner well known and not herein necessary fully to describe.

Referring to Fig. 5, it is to be understood that the needle cylinder is rotating in a counterclockwise direction, and that therefore the sinker cams remain inactive until in the rotation of the needle cylinder the sinker cam ring has been carried frictionally in the direction of the arrow until the screw 26 engages the post 17, whereupon the movement of the sinker cam ring ceases and thereupon the sinkers 20 are moved in and out or radially in the customary manner in cooperation with the knitting wave of the knitting needles.

Preferably the machine is provided with a shaft 29 which may have mounted thereon one or more pattern or cam drums not herein necessary to refer to, and which in this embodiment of my invention also has fast thereon a pattern disk or drum 30 having the elevations 31, 32 functioning during the formation of the leg and the heel of the stocking, and the spaces 33, 34 respectively controlling the formation of the so-called high splice and the formation of the double sole.

The knitting machine is provided with any suitable character of yarn or thread supplying devices. Herein and referring more particularly to Fig. 3, I have represented yarn controlling levers 35, 36, 37,

38, 39 respectively supplying yarn for the high splice, the heel and toe, the so-called boot of the stocking, the upper part of the leg of the stocking, and the introduction of a plating thread. The said levers are mounted in any suitable manner, as, for example, upon a pin 40, shown most clearly in Figs. 3 and 4 in suitable bearings extending upward from the right hand end of the latch ring, and which may be of the general character disclosed in the said Hemphill Patent No. 933,443. Each of said levers is provided with an outwardly extending toe, one of which is indicated at 42 in Fig. 4, and with which preferably cooperate suitable means tending normally to move such lever downwardly into yarn feeding position, that is, into the lowermost position indicated in Fig. 4. Herein for the purpose I have represented a series of levers indicated at 43, 44, 45, 46, 47, pivoted upon the pin 48 in ears 49 upon an upright 41, said levers having tapered or wedge shaped inner ends 50 adapted respectively to take under the respective thread or yarn guides or levers and to move the same downwardly into knitting position under the force of the springs 51 respectively connected to said levers 43-47, and to suitable pins 52 carried by said upright 41. In this or in any other suitable manner, each yarn lever is moved downwardly into action by its spring 51, but is moved upwardly out of action in any suitable manner, as, for example, by the means shown in the said Hemphill Patent No. 933,443, and in the Hemphill Patent No. 934,969, such means being herein typified by levers, one of which is indicated at 53 in Fig. 4 as pivoted upon a pin 54 in said upright 41 and having connected thereto suitable wires or rods 55, extending downwardly into operative relation to a suitable cam or pattern drum upon the cam shaft 29 in a manner not herein necessary more fully to describe.

In accordance with my invention and especially the particular embodiment thereof herein represented, I have provided means whereby the circumferential relation of the sinker cams and therefore the radial position of the sinkers at the effective point of the knitting wave, that is to say, at the point where the yarn is taken by the descending needles, may be varied or changed for any suitable purpose, but especially for the purpose of permitting the introduction of a splicing or reinforcing thread when and where the stitches are lengthened. While for this purpose any suitable means may be provided, I have herein represented the lug or ear 28 as having tapped thereinto an adjustable screw 56 shown most clearly in Figs. 2 and 6, and with which is adapted to operate an abutment here shown as a cam

57 upon a lever arm 58 pivoted at 59 upon the post 17 as clearly indicated in Figs. 2 and 6. To the arm 60 of said lever is pivoted at 61 a link 62, to the lower end of which is pivoted at 63 a lever arm 64 fast upon a shaft 65, itself mounted in bearings 66 and 67 carried by a bracket 68 secured to the upright 69 of the machine. Also fast upon the shaft 65 is a lever arm 70 which extends 10 downward into the vicinity of the cam plate or disk 6 as most clearly shown in Fig. 1 and as having a head or roll 71 adapted for engagement with the periphery of the said cam plate and to ride upon the elevations 7 thereof or to enter the depressions 8 between said elevations. Assuming that the said lever arm 70 with the roll 71 is permitted freely to ride upon the periphery of the cam plate or disk 6, it will be evident that when 15 the roll 71 enters one of the depressions 8 the link 62 and the lever arm 60 will be moved upward viewing Fig. 1, and that the cam 57 will be moved into the path of the supplemental screw or stop 56. When however, said roll 71 rides upon one of the elevations 7, then the cam 57 will be withdrawn from the path of the screw or stop 56.

When the cam 57 is positioned in the path of the screw or stop 56 as indicated in Fig. 6, then in the rotation of the needle cylinder in a contraclockwise direction, viewing Fig. 6 the sinker cam ring will engage with the post 17 (or rather with the cam 57 upon said post 17) at an earlier period in the rotation 30 of the needle cylinder than occurs when said cam 57 is positioned as shown in Fig. 5 out of the path of the screw or stop 56. The consequence therefore is that the movement of the sinker cam ring with the needle cylinder is stopped or prevented at an earlier period and therefore the sinkers 20 are moved in radially to a greater extent at the needle which is depressed to the greatest extent in the formation of the knitting wave, the position of which needle substantially 40 coincides with the radial line 72 in Fig. 6, said lowermost needle being the needle to the left or to the right of said line 72. Viewing Fig. 6, the position of the sinker at the line 72 and the two or more sinkers to the right of said line looking inward toward the centre of the needle cylinder is advanced inward radially to a greater extent than would be the case if the said sinkers were the cam 57 not in operative position with relation to the screw or stop 56 as explained. The effect, therefore, is to draw more yarn between the needles where the yarn is taken by the needles and therefore to increase the length 50 of the stitches which in this application of my invention is particularly intended to permit the introduction of a reenforcing or strengthening thread.

I have stated that my invention while of general application is particularly adapted

for use when a splicing or reenforcing thread is to be inserted. In the disclosed embodiment of my invention, I have represented the high splice yarn lever 35, and in Fig. 4, I have indicated said lever in its lowermost or active position. The high splicing yarn is customarily introduced at the rear of the stocking just above the heel and if desired it extends into the upper part of the heel. Inasmuch as such yarn is introduced at the rear portion only of the stocking, means are provided for withdrawing the yarn lever from action during a part of the knitting of each course of a series of courses, either with or without severing the yarn as it is withdrawn. The yarn may be severed when withdrawn and again where introduced or it may be floated at both the points of introduction and withdrawal, to be afterwards severed, or in any suitable manner 85 the yarn may be manipulated so as to be knitted into each of a series of courses throughout a part only of each of said courses.

In Fig. 4, I have represented the high splice yarn lever 35 in its lowermost or knitting position, and also in said figure, I have represented an intermediate position of a yarn guide 36 this corresponding to the position that will be occupied by the high splice yarn lever 35 during those portions of said courses when the yarn is not being introduced, but has been severed or is being floated. I have also in said figure indicated a yarn guide 39 in its uppermost position, 95 this corresponding to the position that will be occupied by the high splice yarn lever when said high splice yarn lever is wholly out of action.

Although I have referred specifically to 105 the high splice yarn lever 35, it will be understood that said lever also controls the introduction of yarn for the bottom of the foot, or that a separate lever may be provided for such purpose.

In order to move said yarn lever 35 from its lowermost or active position shown in Fig. 4, to its momentarily inactive intermediate position indicated by the position of the yarn guide 36 in said figure, I may provide any suitable means. Herein for the purpose I have provided the needle cylinder 12 with a cam 73 shown most clearly in Fig. 4 and having an inclined edge 74. In the movement of rotation of said needle cylinder said cam 73 engages with and depresses a lever arm 75 which is pivoted at 76 upon the upright 41 and is provided with an arm 77, the end 78 whereof takes under the face or shoulder 79 upon the corresponding lever 53 so as to elevate the same slightly and thereby to lift the high splice yarn lever 35 into its intermediate position. It is evident that the supplementary means thus provided for elevating the high splice yarn lever into 130

its intermediate position does not interfere with the subsequent elevation of said high splice yarn lever 35 to its highest point through the action of its connecting rod or

5 wire 55.

Preferably I provide means whereby the cam 57 is held out of action, that is, out of the path of the screw or stop 56, excepting during the formation of the high splice and 10 the double sole. For this purpose any suitable means may be provided. Herein in cooperation with the cam disk 30 and its cams 31, 32 and spaces 33, 34, I have provided a lever 74' pivoted at 75' and having an arm 15 76', the end 77' whereof is adapted to ride upon said elevations 31, 32 or to enter said spaces 33, 34. The opposite arm 78' of said lever, normally held elevated by spring 78", has pivotally connected thereto at 79' a link 20 or rod 80, the upper end of which is provided with a slot 80', and is pivotally connected at 81 to a lever arm 82 also fast upon said shaft 65. Said shaft 65 also has fast 25 thereon a lever arm 83, to which is connected a coil spring 84, the lower end of which is connected to a pin 85 extending from the support 86 of the rod 15. The construction is such that when the end 77' of the lever 74' rides upon either of the projections 30 31, 32, then the link or rod 80 is moved downward, thereby swinging upwardly the lever arm 83 and rocking the shaft 65 counterclockwise so as to elevate the roll 71 of the lever arm 70 entirely out of the path of rotation of the cam plate or disk 6.

When, however, the end 77' of the lever 74' enters one of the depressions 33, 34, the roll 71 is depressed into the path of the periphery of the cam disk or plate 6.

40 Thus, in the present embodiment of my invention, it is only during the formation of the high splice or the double sole that the cam 57 is moved into the path of the screw or stop 56.

45 It will be understood that in the disclosed embodiment of my invention, the stitches are lengthened throughout partial courses only, as, for example, in the high splice and in the sole of the foot. In the remaining 50 half or portion of each of these courses the stitches are of normal length. Obviously within the scope of my invention the length of the stitches may be varied, as by increasing them throughout an entire course or any 55 number of entire courses.

It will be evident from the foregoing description that in the disclosed embodiment of my invention, I have represented one form of means for governing or varying the 60 stitch length, and more especially for the purpose of permitting the effective introduction of a splicing or reinforcing thread.

Having thus described one illustrative embodiment of my invention, I desire it to 65 be understood that although specific terms

are employed, they are used in a generic and descriptive sense and not for purposes of limitation, the scope of the invention being set forth in the following claims.

Claims:

70 1. A circular knitting machine having a needle cylinder, a circular set of needles, a sinker cam ring and a circular set of like sinkers, a set of sinker cams, each of which is adapted to act upon all the sinkers, means cooperating with said abutment and the sinker cam ring to vary the circumferential position of the sinker cams, thereby to vary the radial position of the sinkers at substantially the point of deepest depression of 80 the knitting wave, and means to introduce a splicing yarn at those points where the stitch length is increased by the said action of the sinkers.

2. A circular knitting machine having a 85 rotary needle cylinder, a circular series of needles, an upright post, a sinker cam ring having spaced lugs adapted for alternate engagement with said post to change the relative circumferential position of the sinker 90 cams and the knitting cams, a set of sinker cams, a circular set of sinkers all adapted to be acted upon by the sinker cams, an abutment adapted to be interposed at a face of the post for engagement with one of said 95 lugs, thereby to vary the radial position of the sinkers at substantially the point of deepest depression of the knitting wave and means to introduce a reinforcing thread at those points where the stitch length is 100 increased by the action of the sinkers.

3. A circular knitting machine having a needle cylinder, a circular series of needles, a sinker cam ring having spaced lugs, a stationary post between said lugs and adapted 105 to be engaged by either of them, a set of sinker cams, a circular set of sinkers all adapted to be acted upon by said sinker cams, an abutment adapted to be inserted periodically between one of said lugs and the 110 said post, and means to control the periodicity of insertion of said abutment.

4. A circular knitting machine having a needle cylinder, a circular series of needles, a sinker cam ring having spaced lugs, a 115 stationary post between said lugs and adapted to be engaged by either of them, a set of sinker cams, a circular set of sinkers all adapted to be acted upon by said sinker cams, an abutment adapted to be inserted 120 periodically between one of said lugs and said post, and rotary cam means adapted to control the periodicity of insertion of said abutment, whereby the stitch length may be increased by the sinker action at predetermined times.

5. A circular knitting machine comprising a rotary needle cylinder, a series of needles, an upright stationary post in proximity to the needle cylinder, a sinker cam ring having 125

- ing spaced lugs between which the post is received, a set of sinker cams, a circular set of sinkers all adapted to be acted on by said sinker cams, a cam adapted to be positioned between the post and one of said lugs to vary the radial position of the sinkers at substantially the point of deepest depression of the knitting wave, a lever to operate said cam together with means to introduce a reinforcing yarn at those points where the stitch length is increased by the action of the sinkers. 45
6. A circular hosiery knitting machine having a needle cylinder, a circular series of needles, a fixed abutment, a sinker cam ring having a circular set of like sinkers, a set of sinker cams each adapted to act upon all of the sinkers, means cooperating with said abutment and the sinker cam ring and adapted periodically to be positioned to change the radial position of the sinkers, thereby to vary the stitch length, a splicing yarn guide, a cam shaft having cam formations thereon determining the position of 50 said periodically positioned means at the formation of the leg, the high splice, the heel and the double sole, and operative connections between said cam formations and said periodically positioned means. 55
7. A circular knitting machine having a rotary needle cylinder, a circular series of needles, a stationary upright post adjacent said needle cylinder, a sinker cam ring having spaced lugs each adapted to engage said post to change the relative position of the sinker cams and the knitting cams, a set of sinker cams, a circular set of sinkers all adapted to be acted upon by said sinker cams, and means to vary bodily the circular 60 position of the sinker cams relative to the knitting cams, thereby to vary the radial position of the sinkers at substantially the point of deepest depression of the knitting wave, said means comprising a cam adapted to be inserted between said post and one of said lugs, a cam shaft, and cam means thereon for determining the position of said cam to be inserted between said post and said lug. 65
8. A circular knitting machine having a rotary needle cylinder, a circular series of needles, a stationary upright post adjacent said needle cylinder, a sinker cam ring having spaced lugs each adapted to engage said post to change the relative position of the sinker cams and the knitting cams, a set of sinker cams, a circular set of sinkers all adapted to be acted upon by said sinker cams, and means to vary bodily the circular 70 position of the sinker cams relative to the knitting cams, thereby to vary the radial position of the sinkers at substantially the point of deepest depression of the knitting wave, said means comprising a cam adapted to be inserted between said post and one of said lugs, a cam shaft, and cam means thereon for determining the position of said cam to be inserted between said post and said lug. 75
9. A circular knitting machine having a rotary needle cylinder, a circular series of needles, a stationary upright post adjacent said needle cylinder, a sinker cam ring having spaced lugs each adapted to engage said post to change the relative position of the sinker cams and the knitting cams, a set of sinker cams, a circular set of sinkers all adapted to be acted upon by said sinker cams, and means to vary bodily the circular 80 position of the sinker cams relative to the knitting cams, thereby to vary the radial position of the sinkers at substantially the point of deepest depression of the knitting wave, said means comprising a cam adapted to be inserted between said post and one of said lugs, a lever carrying said cam, and pattern controlled means for determining the position of said lever. 85

In testimony whereof, I have signed my name to this specification.

GEORGE P. BOSWORTH.
